(57) **CLAIM**

The ornamental design for a wireless internet phone, as shown and described.

DESCRIPTION

FIG. 1 is a top front perspective view of a wireless internet phone showing our new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

In FIG. 3, the broken line immediately adjacent the claimed surfaces represents a boundary of the claimed design, and the broken line on the interior of the boundary line depicts unclaimed environment.
